[57] CLAIM

The ornamental design for a cosmetic dispenser, as shown and described.

DESCRIPTION

FIG. 1 is a perspective view as seen from the top, front and right side of a cosmetic dispenser showing my new design; FIG. 2 is a front elevational view thereof, the rear elevation being a mirror image thereof;

FIG. 3 is a right side elevational view thereof, the left side elevation being a mirror image thereof;

FIG. 4 is a top plan view thereof;

FIG. 5 is a bottom plan view thereof;

FIG. 6 is a perspective view as seen from the top, front and right side of a second embodiment of the cosmetic dispenser disclosed in FIG. 1; and,

FIG. 7 is a front elevational view of the embodiment shown in FIG. 6.
